UNITED STATES PATENT OFFICE

BERNARD A. MALKIN, OF LACHINE, QUEBEC, CANADA

DRIVING MECHANISM FOR PAPER-MAKING MACHINES.

Application filed October 27, 1928. Serial No. 315,465.

This invention relates to new and useful improvements in paper-making machines and particularly to the drier sections thereof, and the main objects of the invention are to provide a drier section which will allow easy access to the interior of the machine from the gear side; which will be economically erected and which will take up less floor space than any of the machines of this type at present in use.

Another object is to provide a drier section in which all or any number of the drier rolls are to be operated in unison.

According to my invention, I provide a plurality of drier rolls which are rotatably mounted on framing members, and driven through the medium of main and idler gears positioned at one side of the machine: The framing members at this side are recessed to receive therein the said gears and suitable covers are secured to the said framing members to enclose the gears and allow easy access to the interior of the machine from this side. Some of the idler gears are so arranged in the casing or framing members that they may be adapted to control the number of rolls which may be driven from any driving unit.

In the drawings which illustrate one form of my invention:

Figure 1 is a side elevation of part of a paper drying machine made in accordance with my invention;

Figure 2 is a part plan of the machine shown in Figure 1.

Figure 3 is an enlarged part sectional end elevation of the machine taken on the line 3—3 Figure 1.

Figure 4 is a front elevation of an eccentric bearing for supporting some of the idler gears.

Figure 5 is a sectional side elevation taken on the line 5—5, Figure 4.

Figure 6 is a view of a modified type of gear support.

Referring more particularly to the drawings, 11 designates the upper rolls and 12 the lower rolls which are secured to and adapted to rotate with the spindles 13 and 14 respectively. The spindles rest on bearings 15 which are preferably of the antifriction

type and mounted in the side framing members 16 and 17 of the drier. These rolls are preferably arranged as shown, that is, the upper roll is positioned between and above the lower rolls. Mounted in suitable bearings 18, depending from the side frame between the upper rolls, are the guide rolls 19. Guide rolls 20 are mounted in bearings 21 secured to the framing members and between the lower rolls. The upper felt 23, which is of the endless type, passes over the top of the upper rolls and under the guide rolls therebetween. The lower felt 24, which is also of the endless type, passes under the drier rolls and over the lower guide rolls. The paper sheet 25 passes under the lower rolls and over the upper rolls alternately through the machine and between said rolls and the felts.

This construction is well known in the art, and my improvement lies in the frame construction and the driving mechanism contained therein. The spindles on one side of the machine extend beyond the bearings and secured thereto are the toothed gears, 26 and 27. Positioned between the lower toothed gears 26 and adapted to mesh therewith are the idler gears 28. Idler gears 30 are also positioned between the gears 28 and the upper toothed gears 27. It will be seen that all the rolls, when the gears are meshing with one another, may be driven from a common source, such as the driving pinion 29 which may be coupled to a driving motor, not shown.

The supporting frame 17 on the gear side of the machine is provided with a plurality of outwardly extending flanges 31 which extend beyond the outer edges of the gears. These flanges are preferably formed radially with the centre of the gears but clear of the teeth thereof. Covers 32 and 33 may be secured to the flanges to totally enclose the gears. This construction forms a frame for supporting the drier rolls and guide rolls as well as forming a gear case totally enclosing the gears, and this gear case may be made oil tight. Bearings 34 and 35 are provided for supporting the upper and lower idler gears respectively. Bearing 34 consists of bearing cups 36 secured to the casing and adapted to

- hold therein the antifriction bearings 37 which support the ends of the idler wheel shafts 38. The parts of the bearing cup 36 which fit into the casing are concentric with the bearing. The bearings 35, a detail one of which is shown on Figures 4 and 5, have each a cup 39 to receive the antifriction bearing 40 which supports the end of the spindle or shaft 41 to which the idler gear is attached.
- 10 The surface 42 in contact with the frame cover is eccentric with the centre of the cup of spindle 41. The bearings 35 are secured to the frame by means of the studs 43 and dowel pins 44 are provided to hold the bearing in place. It will be seen that two or more dowel pin holes are provided in the bearing flange so that the bearing may be so positioned to bring the idler supported thereon into or out of engagement with the idler above and at 15 each side of the bearing. The throw of eccentricity being slightly greater than the depth of the teeth of the idlers so that the idlers mounted on the eccentric bearings may be thrown into and out of mesh by the turning 20 movement of the bearing.

In operation it will be seen that the side frame on the gear side supports the drier rolls as well as forming a gear case for the driving and idler gears of the machine. By 30 mounting the gears within the framing and using the antifriction bearings for the rolls, the amount of floor space occupied by the machine is much less than machines where the gears are positioned without or overhung from the frame. Access to the interior of the machine is easily obtained as the operator can get nearer to the machine than the present type of machine. The covers being secured to the frame totally enclose the gears so that they may run in oil and reduce wear 40 and maintenance charges to a minimum. Another feature about providing bearings in the covers and in the frame is that idler wheel spindles are supported at both ends and not overhung from the frame. It also allows the idler wheel bearings to be made eccentric so that they may be turned to allow all or any 45 number of the rolls to be moved from a common source. The eccentric bearings are preferably mounted between the bottom roll bearings as shown.

The provision of an enclosed frame adapted to totally enclose the gears ensures safe 50 operation of the machine without sacrificing valuable floor space.

In Figure 6 the idler gear wheel is rotatably mounted on an eccentric spindle 46 the ends of which are supported on suitable bearings 47 and 48 formed in the side of the frame and cover. The end 49 of the spindle may have a handle 50 attached thereto to facilitate the turning of the spindle to place the idler gear into or out of mesh with the adjacent 60 toothed wheels thus providing means for

quickly altering the number of driven rolls in each section of the drier.

The mechanism shown is only for illustrative purposes, and it will be readily understood that many modifications may be made to the positioning of the rolls, the type of bearing and the shape of the framing members without departing from the spirit of the invention.

Having thus described my invention, what I claim is:—

1. In a paper-making machine a plurality of drier rolls, side framing members adapted to rotatably support the drier rolls, a plurality of gears adapted to rotate said rolls, said gears being positioned within the framing members.
2. In a paper-making machine, a plurality of drier rolls, side framing members adapted to rotatably support the rolls, a plurality of driving gears for the rolls, said gears being positioned within one of the framing members and covers secured to the frame to totally enclose the said gears.
3. In a paper-making machine, a plurality of drier rolls, roll spindles secured thereto, bearings for rotatably supporting the spindles, driving gears secured to the spindles for rotating the rolls, side framing members for supporting the bearings, said members being recessed to receive the gears and covers for the framing members to enclose the gears.
4. In a paper-making machine a plurality of drier rolls, a plurality of guide rolls, a train of gears for rotating the drier rolls, and side framing members adapted to totally enclose the gears and support the drier and guide rolls.
5. In a paper-making machine, a plurality of drier rolls, a plurality of guide rolls, means for rotating said rolls, and framing members for supporting the guide rolls and drier rolls, one of said members being adapted to totally enclose the roll rotating means.
6. In a paper-making machine, a plurality of drier rolls arranged in two horizontal rows, spindles for said rolls, bearing for the spindles, gear wheels at one end of each of the drier roll spindles, idler gear wheels between the aforementioned idlers and the upper rolls gears and side framing members for supporting the roll bearing spindles, and the idler gears, and the guide rolls, one of said members being adapted to totally enclose the idler gears and the roll driving gears secured to the spindles.
7. In a paper-making machine, two rows of paper drying rolls, felt guide rolls between each pair of rolls in the same row, roll spindles secured to the rolls, side framing members for supporting the guide roll spindles and the guide rolls, toothed gears secured to each drier roll spindle, idler toothed wheels between each pair of lower roll gears, and adapted to mesh therewith,

5 idler toothed wheels between the lower idler wheels and the upper roll gears, covers secured to the frame on one side of the machine to totally enclose the gears and bearings in the framing member and the cover to rotatably support the idler gears.

8. In a paper-making machine, a plurality of drier rolls arranged in two horizontal parallel rows, framing members, having 10 bearings adapted to rotatably support the rolls, felt guide rolls, between the drier rolls and supported on the framing members, toothed wheels secured to the drier rolls, idler toothed wheels between the lower roll 15 gears and adapted to mesh therewith, idler toothed wheels between the lower idler rolls and the gears of the upper rolls, means to drive the gears, bearings in the framing for supporting the idler wheel, the bearing for 20 the lower idler wheels being made eccentric so that the train of gearing may be altered to drive all or any number of the drier rolls.

9. In a paper-making machine, a plurality of drier rolls arranged in two parallel rows, 25 framing members adapted to rotatably support the rolls, toothed wheels secured to the drier rolls, idler toothed wheels between the gears of the lower rolls, a second set of idler toothed wheels between the lower idler 30 wheels and the upper roll gears, said lower idlers being mounted eccentrically to allow the train of gearing to be altered to vary the number of rolls driven by any one unit, and means secured to the framing members to 35 totally enclose the gears.

In witness whereof, I have hereunto set my hand.

BERNARD A. MALKIN.
